UNITED STATES PATENT OFFICE

ALEXANDER RIMBERG, OF BROOKLYN, NEW YORK

DESIGN FOR A LAMP

Application filed March 27, 1931. Serial No. 39,265. Term of patent 3½ years.

To all whom it may concern:

Be it known that I, ALEXANDER RIMBERG, a citizen of the United States, residing at Brooklyn, in the county of Kings and State of New York, have invented a new, original, and ornamental Design for a Lamp, of which the following is a specification, reference being had to the accompanying drawing, forming part thereof.

The figure is a plan view of a lamp showing my new design.

The opposite side of the design shown is complementary thereto.

I claim:

The ornamental design for a lamp as shown and described.

ALEXANDER RIMBERG.
